UNITED STATES PATENT OFFICE.

SIMON W. WARDWELL, OF PROVIDENCE, RHODE ISLAND, ASSIGNOR TO WARDWELL BRAIDING MACHINE COMPANY, OF PORTLAND, MAINE, A CORPORATION OF MAINE,

DESIGN FOR A TWINE-HOLDER.

46,079.

Specification for Design.

Patented July 7, 1914.

Application filed April 17, 1914. Serial No. 832,652. Term of patent 14 years.

To all whom it may concern:

Be it known that I, SIMON W. WARDWELL, a citizen of the United States, residing at Providence, in the county of Providence and State of Rhode Island, have invented a new, original, and ornamental Design for Twine-Holders, of which the following is a specification, reference being had to the accompanying drawing, forming part thereof.

The figure is a perspective view of a twine holder embodying my new design.

I claim:

The ornamental design for a twine-holder as shown.

In testimony whereof I affix my signature in presence of two witnesses.

SIMON W. WARDWELL.
